UNITED STATES PATENT OFFICE.

ORRIN FITZGERALD, JR., OF DEXTER, MAINE.

SMOKE AND SPARK CONVEYER FOR LOCOMOTIVES.

SPECIFICATION forming part of Letters Patent No. 369,050, dated August 30, 1887.

Application filed October 11, 1886. Serial No. 215,942. (No model.)

To all whom it may concern:

Be it known that I, ORRIN FITZGERALD, Jr., a citizen of the United States, residing at Dexter, in the county of Penobscot and State of Maine, have invented certain Improvements in Smoke and Spark Conveyers for Railway-Trains, of which the following is a full, clear, and exact description, reference being had to the accompanying drawings, 10 making a part of this specification, in which—

Figure 1 is a sectional elevation of a locomotive-engine having my improved smoke and spark conveyer applied thereto. Fig. 2 is a plan of the same.

15 My invention relates to certain improvements in that class of smoke and spark conveyers for railway-trains in which a pipe or system of pipes is employed to receive the smoke and cinders from the smoke-stack of the 20 locomotive-engine and conduct the same to the rear, the object of my invention being to so improve the construction of the parts as to create a strong rearward air-current through the conveyer, and thus prevent any interference 25 with the draft of the furnace and consequent rapid generation of steam.

To this end my invention consists in the combination, with a locomotive-engine having a rearwardly-inclined smoke-stack, of a horizontal conveying-pipe provided with an open flaring or trumpet-shaped mouth located at the rear of the base of the smoke-stack and facing toward the front of the locomotive, and arranged opposite to or in line with the discharge-orifice of said smoke-stack, but entirely disconnected therefrom, and adapted to receive the smoke, sparks, &c., discharged from said smoke-stack, the said flaring mouth being open to the atmosphere, whereby when the 30 train is in motion a strong inward and rearward air-current will be produced throughout the entire length of the conveying-pipe, which will carry with it all the smoke and sparks, which will thus pass through the conveying-pipe without resistance, the tendency being to increase rather than diminish the draft of the furnace, thus facilitating instead of retarding the generation of steam, as hereinafter more particularly set forth; and my invention further 35 more consists in the combinations of devices and in certain details of construction, as hereinafter set forth and specifically claimed.

In the said drawings, A represents a locomotive-engine which is provided with a smoke-stack, B, inclined toward the rear, as 55 shown, the exhaust nozzle or tip *a* being so located and inclined as to discharge the steam in the direction of the longitudinal axis of the said smoke-stack.

C is a smoke-conveying pipe suitably supported and extending horizontally over the locomotive, said pipe being connected at its rear end by means of a suitable joint, D, with another horizontal conveying-pipe, G, secured to the tender or car just behind the same, this 60 pipe being connected, by a joint similar to D, with a pipe on the next car, and so on throughout the length of the train, from the rear end of which the smoke is discharged. This pipe C is provided at its front end with a wide 65 flaring or trumpet-shaped mouth, *b*, located in the rear of the base of the smoke-stack B, and placed opposite to and in line with the discharge-orifice of said stack to receive the smoke, sparks, &c., discharged therefrom. 70

The outer end of the smoke-stack B is located outside or in front of the upper portion of the flaring mouth *b*, and is set back at such distance therefrom as to leave it free to the open air, and thus prevent any back-pressure 80 or obstruction to the draft, which would interfere with the rapid generation of steam, while the current of air which rushes into the flaring mouth *b* will carry with it all the smoke, cinders, &c., discharged from the smoke-stack 85 and cause them to pass freely into the horizontal conveying-pipe C. The lower portion of the edge of the mouth *b* is shaped to fit the top of the boiler *d*, to which it is secured at *e*, and by extending the bottom of the mouth *b* 90 down to the boiler the air is caused to rush in under the end of the smoke-stack, which prevents the cinders from dropping down under the stack, the air acting equally all around the end of the same, as the diameter of the 95 stack is much less than the width of the trough-like lower portion of the mouth *b*.

The conveying-pipe, with its flaring mouth, is preferably located on one side of the center, as seen in Fig. 2, in order to prevent it from 100 interfering with the steam-dome, whistle, safety-valves, &c., on the top of the boiler, this arrangement also enabling the conveying-pipes to be located on one side of the raised or

"monitor" tops of the cars, to allow of a clear passage under low bridges. The flaring mouth *b*, which faces toward the front, being open to the atmosphere and having no direct connection with the smoke-stack, it follows that when the train is in motion there will be a strong inward rush of air into the flaring mouth *b*, whereby a powerful inward and rearward air-current will be created throughout the entire length of the conveying pipe or pipes, which current will carry with it to the point of discharge all of the smoke, sparks, &c., received from the smoke-stack, which will consequently meet with no resistance in their rearward passage, while the air-current will tend to increase the draft of the locomotive-furnace, thus accelerating the generation of steam, instead of retarding the same, as would occur if the smoke-stack were directly connected with the conveying-pipe *C*.

Another advantage resulting from the construction shown is that when the train is at rest and the wind blowing in a direction at right angles to the length of the conveying-pipe the smoke, &c., will pass off to one side between the end of the smoke-stack and the edge of the flaring mouth *b* without having to pass through the said conducting-pipe *C*.

The interior of the smoke-stack is left clear and free from all obstructions, thus facilitating the discharge of the smoke, sparks, &c., and giving a better draft with increased heat and no interference with the rapid generation of steam.

I is a branch pipe, which extends from the conveying-pipe *G* down between the tender and the front car of the train nearly to the ground, to discharge the sparks and cinders onto the road-bed, the conveying-pipe at its junction with the pipe *I* being provided with a curved deflector, *m*, for directing the sparks and cinders into the said pipe *I*, and having an inclined guard, *p*, composed wholly or partially of woven wire, which intercepts and prevents the sparks and cinders from passing with the smoke again into the horizontal conveying-pipe beyond.

By the employment of my improved smoke and spark conveyer the annoyance and dis-

comfort usually experienced by the passengers from the entrance of smoke and cinders is avoided, and the interior of the cars can consequently be kept perfectly clean. Furthermore, the extinction of any live sparks is insured, and the setting on fire of bridges and other property along the line of the track by passing trains is thus effectually prevented.

What I claim as my invention, and desire to secure by Letters Patent, is—

1. An improved smoke and spark conveyer for railway-trains, comprising the combination, with a locomotive-engine having a rearwardly-inclined smoke-stack, of a horizontal conveying-pipe provided with a flaring or trumpet-shaped mouth having its lower edge extended down to the boiler at the rear of the base of said stack, said mouth being in line with the discharge of the smoke-stack, whereby it receives the smoke and sparks, substantially as herein described.

2. In a smoke and spark conveyer for railway-trains, the combination, with a locomotive-engine having a rearwardly-inclined smoke-stack, *B*, of a horizontal conveying-pipe, *C*, provided with a flaring or trumpet-shaped mouth, *b*, entirely disconnected from the smoke-stack, and having its lower edge extending down to the boiler at the rear of the base of the said smoke-stack, and located opposite to and in line with the discharge-orifice of the said stack, and the exhaust-nozzle having its discharge end inclined to correspond with the inclination of the stack, substantially as and for the purpose described.

3. In a smoke and spark conveyer for railway-trains, the combination, with the horizontal smoke and spark conveying pipe *G*, of a downwardly-extending branch pipe, *I*, adapted to conduct the sparks and cinders to the ground, and having a deflector, *m*, and a guard, *p*, all operating substantially in the manner and for the purpose set forth.

Witness my hand this 7th day of October, A. D. 1886.

ORRIN FITZGERALD, JR.

In presence of—

P. E. TESCHEMACHER,
DWIGHT BALDWIN.
